(57) **CLAIM**

The ornamental design for an electronic article surveillance pedestal with two-sided display, as shown and described.

DESCRIPTION

FIG. 1 is a front, right perspective view of an electronic article surveillance pedestal with two-sided display embodying our new design;

FIG. 2 is a bottom right perspective view thereof;

FIG. 3 is a front view thereof;

FIG. 4 is a back view thereof;

FIG. 5 is a right-side view thereof;

FIG. 6 is a left-side view thereof;

FIG. 7 is a top view thereof; and,

FIG. 8 is a bottom view; thereof.

1 Claim, 8 Drawing Sheets
